Inventor:
Janoskar Benda.

UNITED STATES PATENT OFFICE.

JAROSLAV BENDA, OF PRAGUE, CZECHOSLOVAKIA.

FOOTWEAR.

Original application filed October 11, 1924, Serial No. 743,140, and in Czechoslovakia October 19, 1923.
 Divided and this application filed May 8, 1926 Serial No. 107,820.

This application is a division of copending application Serial No. 743,140, filed October 11, 1924.

This invention relates to boots and the like of the kind in which the margin of the insole is bent upwards so that the middle portion of the same can be placed flat against the outer sole without any intervening filling material.

10 In known boot constructions of this kind, the insole is channelled to form sewing lips for connection to the welt, and only the comparatively narrow sole margin which is thinned down by the channeling bends upwards in a gradually developing curve.

15 The object of the present invention is to produce an inner boot surface which is more in conformity with the natural shape of the sole of the foot and presents to the latter a substantial concavity in which it is comfortably supported, and the invention consists in forming the insole with a margin of substantial width and in maintaining the shape of the cavity by the insertion of a leather or like strip of triangular cross-section between the two soles immediately behind the sewing lip.

20 The sewing lip is moreover composed of a strip which is cemented to the insole so that the latter can be made of thin material the better to adapt itself to the formation of the cavity.

25 Fig. 1 of the accompanying drawings represents a cross-sectional outline of the foot and shows the angular position of the insole margin.

Fig. 2 is a cross-section of the boot, and

Fig. 3, a horizontal section of the same.

30 The insole 6 of the boot or shoe 9 is formed with a margin 2 which is inclined relative to the middle portion 1 at an angle of about 20°. The width of the margin represents from 1/5 to 1/4 of the widest portion of the sole, but the width as well as the inclination may vary slightly according to requirements at 35 different parts of the same sole. The margin is bent up so as to present a distinct boundary line 4 which usually, i. e., when the boots are right and left sided, extends right round the sole from and to the inside 3 of the waist where the margin merges directly into the

middle portion. In boots made on straight lasts, the distinction between the margin and the middle portion is omitted at both sides of the waist.

The insoles are planned out systematically, the same proportions of margin relative to the middle portion being maintained for all the different sizes.

Fig. 1 illustrates the position of the margin relative to the foot R and above its inclination α relative to the undersurface p of the sole of the foot.

The sewing lips whereby the insole is connected to the welt, are cemented to the insole which can therefore be made of thin material. The middle portion 1 of the insole bears directly on the outer sole 7, and wedge-shaped strips 5 of cork, leather or the like are inserted to fill up the gap left behind the sewing lip between the margin 2 and the sole 7.

Although shown in connection with a welted shoe, the features of the invention are also applicable to other kinds of shoes and boots.

I claim:

1. In boots and shoes of the character described, an insole having an inclined margin of a width representing from 1/5 to 1/4 of the widest portion of the insole extending right round the latter except at the inside of the waist, said margin being inclined so as to present a concave surface to the foot.

2. In boots and shoes of the character described, an insole having an inclined margin of a width representing from 1/5 to 1/4 of the widest portion of the insole extending right round the latter except at the inside of the waist, said margin being inclined relative to the body portion of the sole at an angle of about 20° so as to present a concave surface to the foot.

3. The insole structure claimed in claim 2, a sewing lip cemented to the underside of the inclined margin, and a supporting strip of triangular cross-section arranged on the margin behind said lip, the supporting strip and the free edge of the sewing lip being flush with the central body portion of the insole.

In testimony whereof I have signed my name to this specification.

JAROSLAV BENDA.
